UNITED STATES PATENT OFFICE.

MELACH J. NUSIM, OF EASTON, PENNSYLVANIA, ASSIGNOR TO INGERSOLL-RAND COMPANY, OF JERSEY CITY, NEW JERSEY, A CORPORATION OF NEW JERSEY.

COMBINED GAS EXHAUSTER AND TAR EXTRACTOR.

Application filed May 20, 1924. Serial No. 714,570.

To all whom it may concern:

Be it known that I, MELACH J. NUSIM, a citizen of the United States, and a resident of Easton, county of Northampton, and 5 State of Pennsylvania, have invented a certain Combined Gas Exhauster and Tar Extractor, of which the following is a specification accompanied by drawings.

This invention relates to blowing apparatus and more particularly to exhausters of the centrifugal type which is intended to operate on fluids, such as illuminating gas, which carry in suspension heavy liquid or semi-solid matter as, for instance, tar which 15 it is desired to separate from the gas.

It is an object of this invention to combine the operations of exhausting and tar separation in a single apparatus.

In the manufacture of illuminating gas, 20 the gas which is exhausted from the coke oven or similar apparatus, carries in suspension small quantities of heavy oils or tar which are apt to collect in and clog the pipes. It is proposed by this invention to combine 25 apparatus for exhausting or compressing the gas and simultaneously extracting the tar. This is accomplished in a preferred form of the invention by use of a centrifugal impeller which accelerates the gas to a high velocity and projects it through a diffuser into 30 a curved passage which leads to a pressure chamber and also to a tar collecting chamber, the latter being situated somewhat beyond the pressure chamber. Due to the high 35 velocity of the mixture of gas and tar, the tar is projected tangentially as the mixture follows the curved passage and such tar as adheres to the walls and radial plates provided for this purpose will be gradually 40 moved forward by the gas blowing thereagainst until it reaches the dead space provided by the tar collecting chamber.

The invention will be more clearly understood by reference to the following description 45 taken in conjunction with the accompanying drawings in which similar reference characters refer to similar parts.

Figure 1 is a vertical longitudinal section 50 of a combined gas exhauster and tar extractor of the centrifugal type constructed in accordance with the practice of this invention, and

Figure 2 is a cross section taken along the 55 line 2-2 looking in the direction of the arrows.

Referring to the drawings, the blower comprises a casing A within which are rotatably mounted a plurality of impellers B which are adapted to draw gas from an inlet C formed integrally with the casing A and by centrifugal force to expel it through diffusers D adjacent the outlet of the impellers and extending radially therefrom. The blower may be of the single stage or multi-stage type as desired. In this instance, there being three impellers shown, the apparatus is of the three stage type. Between the impellers B there are provided pressure chambers E adjacent the diffusers which are adapted to receive the gas forced 60 by the impellers B through the diffusers D and to deliver it to the next succeeding impeller. The pressure chambers E are so arranged that the gas entering them from the diffusers D is obliged to change its direction 65 180° following longitudinal passages D' leading from the diffusers D to the pressure chambers E and tar collecting chambers F. In so doing, the tar or relatively heavy matter held in suspension is thrown out tangentially and is projected into the tar collecting 70 chambers F situated beyond the pressure chambers E with respect to the diffusers D. There are no gas outlets provided in the tar collecting chambers F and therefore there is 75 substantially no current of gas therein. Baffles G arranged circumferentially about the entrance to the chambers F are adapted to further prevent gas circulation within the chambers and also to assist in further tar 80 separation as the gas impinges on these 85 baffles.

As the gas issues from the diffusers D the tar may be projected against the outer walls 90 of the pressure chambers E, but due to the current of gas which impinges thereagainst, the tar from the upper half of the passage 95 D' will work its way along the walls into the collecting chambers F. The lower half of the chambers F is cut off from communication with the intermediate pressure chambers E by a wall K upon which the tar from the upper half of the collecting chamber drops and passes out through an aperture L in alignment of the aperture J thence into the sump H. By gravity the tar separated 100 in the lower half of the passage D' will find its way through the same aperture J into the sump H. Preferably, the impellers B are mounted 110

on a single shaft O by which they are rotated and which may be suitably journalled in the casing A. Seals P may be provided to prevent leakage between the impellers B 5 and the adjoining chambers.

The fluid pressure on opposite sides of the impellers B is unequal because of the difference in the areas against which they act and therefore there is preferably provided 10 a counter balancing drum Q exposed at its inner side to the maximum pressure developed within the blower, and at its outer side either to the negative pressure of the inlet C or to atmosphere. In this manner, the 15 end thrust on the shaft O is eliminated. The diffuser D on the last stage may, if desired, lead directly to the outlet R and thence to suitable conduits for consumption or storage.

I claim:

- 20 1. A combined gas exhauster and tar ex-tractor for gas, comprising a casing, an im-peller rotatably mounted within the casing, a diffuser adjacent the outlet of said im-peller and extending radially therefrom, a pressure chamber having an outlet, a tar collecting chamber remote from said diffuser and hav-ing no outlet for gas, and a longitudinal passage leading from said diffuser to said pressure chamber and said collecting chamber.
- 25 2. A combined gas exhauster and tar ex-tractor for gas, comprising a casing, an im-peller rotatably mounted in said casing, a diffuser extending radially from said im-peller, a pressure chamber adjacent said diffuser, a longitudinal passage leading from said diffuser to said pressure chamber, and a tar collecting chamber remote from said diffuser and connected thereto by said longi-tudinal passage, said pressure chamber being disposed between said diffuser and said col-lecting chamber.
- 30 3. A combined gas exhauster and tar ex-

tractor for gas, comprising a casing, a plu-45 rality of impellers mounted for rotation within said casing, a diffuser for each im-peller, pressure chambers disposed adjacent said diffusers, a tar collecting chamber for certain of said diffusers and formed in-tegrally therewith and longitudinal passages 50 associating said diffusers with their corre-sponding pressure chambers and collecting chambers and disposed at an angle to said diffusers to cause the tar to be centrifugally separated from the gas and carried beyond 55 said pressure chamber to the collecting chamber.

4. A combined gas exhauster and tar ex-tractor for gas comprising a casing, an im-peller rotatably mounted within the casing, 60 a diffuser adjacent the outlet of said im-peller and extending radially therefrom, a pressure chamber having an outlet, a tar collecting chamber remote from said dif-fuser and having no outlet for gas, a longi-tudinal passage leading from said diffuser 65 to said pressure chamber and said collecting chamber, and a wall separating the lower half of said longitudinal passage from said collecting chamber to prevent the return of 70 tar to said passage.

5. A combined gas exhauster and tar ex-tractor for gas, comprising a casing, an im-peller rotatably mounted within the cas-ing, a diffuser adjacent the outlet of said 75 im-peller and extending radially therefrom, a pressure chamber having an outlet, a tar collecting chamber remote from said dif-fuser and having no outlet for gas, a longi-tudinal passage leading from said diffuser 80 to said pressure chamber and said collecting chamber, and radial baffles in said collecting chamber to collect tar by contact therewith.

In testimony whereof I have signed this specification.

MELACH J. NUSIM.
